PAINT BRUSH HANDLE

John A. Pharris, Brookfield, and Albert A. Mlachnik,
Greendale, Wis., assignors to EZ Paint'r Corporation

Filed Sept. 25, 1970, Ser. No. 25,204

Term of patent 14 years

Int. Cl. D4—04

U.S. Cl. D4—38

FIG. 1 is a side elevational view of a paint brush handle embodying the design of our invention.

FIG. 2 is an end elevational view taken from the left hand side of FIG. 1.

FIG. 3 is an end elevational view taken from the right hand side of FIG. 1.

FIG. 4 is a side elevational view taken from the side opposite that shown in FIG. 1; and

FIG. 5 is a top plan view thereof.

We claim:

The ornamental design for a paint brush handle, as shown.
